UNITED STATES PATENT OFFICE.

OTTO SIEMEN, OF NONNENDAMM, NEAR BERLIN, AND WERNER SIECKE, OF BERLIN, GERMANY, ASSIGNEES TO SIEMENS-SCHUCKERTWERKE, G. M. B. H., OF BERLIN, GERMANY, A CORPORATION OF GERMANY.

ROTARY BLOWER OR PUMP.

1,322,363.

Specification of Letters Patent. Patented Nov. 18, 1919.

Application filed April 1, 1913, Serial No. 758,197. Renewed August 7, 1917. Serial No. 164,976.

To all whom it may concern:

Be it known that we, OTTO SIEMEN and WERNER SIECKE, citizens of the German Empire, and respectively residing at Nonnendamm, near Berlin, and Berlin, Germany, have invented certain new and useful Improvements in Rotary Blowers or Pumps, of which the following is a specification.

Our invention relates to rotary blowers or pumps in which a rotating ring of liquid constitutes the packing between the blades of the blade-wheel and the casing and the inlet and outlet openings for the medium which is sucked into the blower or pump. 10 In such pumps the blade-wheel is arranged eccentrically in the bore of the pump casing. The water introduced into the casing is driven by the rapidly rotating blades and in consequence of the centrifugal force 15 forms a ring which fills up the space between the inner face of the casing and the outside boundary of the inlet and outlet openings.

According to our invention the interior 20 periphery of the casing is not circular, but bulges outward on the suction side and, if desired, on the discharge side of the pump. We hereby provide that the packing between the suction and discharge sides is 25 more favorable than heretofore, and that when the speed and the ratio of the suction and discharge pressures vary, more favorable operation is obtained.

In the accompanying drawings Figure 1 shows a section through a pump for conveying air according to our invention, said section being taken at a right angle to the shaft of the pump, Fig. 2 shows a section parallel to the shaft of said pump, Fig. 3 a section 30 through a pump similar to Fig. 1 differing from the latter in that the outlet consists of a plurality of valve openings, Fig. 4 is a side view of the pump shown in Fig. 3 comprising also a disk preventing the medium being conveyed from flowing around from one blade to the other, Fig. 5 a section 35 through a pump construction having a clearance or overflow passage, Fig. 6 a side view to Fig. 5, Fig. 7 a construction of a pump with two inlets which are displaced by approximately 180° and correspondingly displaced outlets.

Referring to the drawing, *a* designates

the blade-wheel journaled eccentrically relatively to the bore of the casing *d*, and *b* designates the suction or inlet opening and *c* the discharge or outlet opening for the air. The inside face of the casing *d* deviates from the circular, as indicated by a dotted line, and is bulged or curved outward on the suction side and also on the discharge side. The bulges enable both the suction opening *b* and the discharge opening *c* to be located very near the crown *g* of the blade-wheel. A principal advantage thereby obtained is that the distance between the suction and discharge openings is increased. Consequently, compression takes place over a longer distance and the rise of pressure between each two stages of such two blades 70 of the pump-wheel is relatively small. The packing is consequently considerably more reliable.

The peculiar formation of the inside wall of the pump according to our invention, 75 however, also causes more uniform conditions during working when the speed of the pump or the ratio of the pressures on the suction and discharge sides of the pump vary. The water line, *i. e.* the inner periphery of the ring of liquid, or the center of the ring of liquid shifts toward the discharge side when the peripheral speed is high and toward the suction side when the same is low. This shifting of the eccentricity has, however, much less action on the suction capacity of the pump when the suction opening is placed very near the crown of the blade-wheel and the casing is bulged, as compared with when the casing has a 90 circular cross-section and, consequently, the suction opening must be located low down. The improved pump or blower according to our invention is consequently less sensitive to changes of speed and of the ratio of 95 pressures at the suction and discharge sides of the pump.

Owing to the wall of the casing bulging outward a radial displacement of the water line on the discharge side is obtained, which 100 displacement allows the free section of outlet of the discharge opening to be considerably increased. Further, the quantity of water supplied for maintaining the ring of liquid is materially diminished because 105 smaller quantities of water are carried along

through the outlet opening. This is of importance particularly when it is required to produce a very high vacuum.

The outlet opening may be made as desired. It is preferable to distribute a number of valves *f*, as shown in Fig. 3 of the drawing, on the discharge side which open, in known manner, only when a predetermined pressure obtains. If the ratio of the pressures existing on the suction and discharge sides is small, the valves located far from the crown will open and allow the medium sucked in to flow through them. When the said ratio is large, however, only the valves located near the crown will open. The advantage of this kind of outlet opening in connection with the herein described formation of the inside wall of the casing is that the path between the suction and discharge sides is longer, the larger the said ratio. The packing is thus caused to adapt itself to the pressure existing for the time being.

The inlet and outlet openings of the sucked-in medium are preferably provided in the end wall of the casing. When they are provided only in the one end, as shown in Fig. 4, the other side of the blade-wheel can be covered by a disk *e* for preventing the medium which is being conveyed flowing around from one blade to the others.

A clearance may exist at the crown *g* of the pump-wheel, the contents of the clearance being at a high pressure. In order to prevent the compressed medium being carried over to the suction side and thereby diminishing the suction space, we may provide in the end wall of the casing a passage *m* which connects the space at the crown *g* with the space *n* of the pump which is at a pressure higher than the initial pressure, as shown in Figs. 5 and 6. Particularly when the ratio of compression is high the sucked-in volume can be kept as large as possible in this arrangement.

It is also possible to combine two pump systems in one casing in order to obtain a double acting pump. In this case each side of the blade wheel is provided with two inlets which are displaced from each other by about 180° and two correspondingly displaced outlets, such as shown in Fig. 7. In this construction the casing is divided into

two halves by the blade wheel, each half representing a pump system of its own. The work of pumping thus will take place within either half of the casing, that is within an angle of 180° . In Fig. 7 *b*, and *b*, are the suction openings, *c*, and *c*, the pressure openings, *i* are the spaces or enlargements which deviate from the dotted line *h* representing the circular cross-section. These bulges or enlargements will render it possible to place the suction and the pressure openings as far as possible from each other.

For increasing the ratio of compression a number of pumps of the kind described may, of course, be connected in series, so that the pressure of the sucked-in medium is raised in stages.

We claim:—

1. In a rotary blower or pump of the character described, the combination of a casing having an inlet opening and an outlet opening, and a blade-wheel mounted eccentrically in the casing and adapted when rapidly rotated, to cause liquid supplied into the casing to assume the form of a rotating ring in the casing, the interior periphery of the casing being bulged or curved outward both on the inlet and on the outlet side thereof in a shape deviating from the circular.

2. In a rotary blower or pump of the character described, the combination of a casing having an inlet opening and an outlet opening, a blade-wheel mounted eccentrically in the casing and adapted, when rapidly rotated, to cause liquid supplied into the casing to assume the form of a rotating ring in the casing, the interior periphery of the casing being bulged or curved outward in a shape deviating from the circular, and a passage connecting the space at the crown of the blade-wheel with a space in the casing containing a pressure higher than the initial pressure.

In testimony whereof we have signed our names to this specification in the presence of two witnesses.

OTTO SIEMEN,
WERNER SIECKE.
